UNITED STATES PATENT OFFICE.

GEORGE BALLARD AND CLARE BALLARD, OF PONTIAC, MICHIGAN.

EXTENSION BED AND SPRING.

1,035,765.

Specification of Letters Patent. Patented Aug. 13, 1912.

Application filed March 27, 1912. Serial No. 686,564.

To all whom it may concern:

Be it known that we, GEORGE BALLARD and CLARE BALLARD, citizens of the United States, residing at Pontiac, in the county of 5 Oakland and State of Michigan, have invented new and useful Improvements in Extension Beds and Springs, of which the following is a specification.

The general object of the invention is to 10 render a bed extensible as to width in order that the bed may be readily converted from a single into a three-quarter or double bed, and conversely from a double into a three-quarter or single bed; and to this end the 15 invention consists in certain improved constructions, arrangements, and combinations of devices, which will be fully described hereinafter, and then pointed out in the claims.

20 Other objects will appear and be better understood from that embodiment of our invention of which the following is a specification, reference being had to the accompanying drawings forming a part hereof, in 25 which;

Figure 1 is a perspective of the invention. Fig. 2 is a detail plan showing one end portion of one of the spring rolls arranged in its bearing and the means for adjustably securing it against turning movement. Fig. 3 is a sectional detail showing the means for securing the rail sections in their adjusted positions. Fig. 4 is a detail 35 vertical cross section showing the means for holding the end rail sections against downward springing, said section being taken on the line 4—4 of Fig. 3. Fig. 5 is a top plan view of the spring rolls and bed spring.

The head piece *a*, foot piece *b*, side rails 40 *c—c* and end rails *d—d* are all of metal, so also are the lugs *e—e* which support the side and end rails and which are formed integral or otherwise suitably connected with the head piece *a* and foot piece *b*. Instead of 45 forming the head and foot pieces each of one section, we form each of said parts of two sections, the sections 5—5 of the head and foot pieces having upper cross bars 6—6 and lower cross bars 7—7, which are 50 suitably connected to the sections 5—5 and which in length, correspond approximately to one-half the length of the cross bars of a double bed. The sections 8—8 of the head and foot pieces are provided with cross bars 55 9—9 and 10—10 which align with the cross bars 6—6 and 7—7 and which are so con-

structed as to loosely receive the said cross bars 6—6 and 7—7, with which they correspond in length. Thus, it will be seen that when the sections 6—6 and 7—7 are moved 60 relatively far out of the sections 9—9 and 10—10, as shown in Fig. 1, the maximum width of the bed will be had and since the combined lengths of the cross bars are now equal to those of the cross bars of a double 65 bed, the bed as now adjusted will conform in width to a double bed. On the other hand when the cross bars 6—6 and 7—7 are moved into the cross bars 9—9 and 10—10 until to three-fourths of their surfaces are fusible, then the width of the bed 70 will correspond to that of the ordinary three-quarter bed and finally when the cross bars 6—6 and 7—7 are moved farther into the cross bars 9—9 and 10—10 and until 75 the combined lengths of the cross bars conform to those of the ordinary single bed, the bed will then conform in width to the width of a single bed.

It is evident that in carrying out the foregoing adjustment as to width, if the end rails *d—d* were each of one piece three sets of these end rails, each of a different length from the others and conforming to the length of end rail required for a bed of certain width, would have to be used. Therefore, in order to obviate the additional cost of a bed which would be made necessary by having to have three sets of end rails, and the difficulty which would be experienced in 80 removing and replacing end rails for each new adjustment and also the work which would be called for in taking the end rails desired to be used, from a place of storage and returning to the storage those removed 85 from the bed, and the annoyance resulting from inadvertently taking the wrong size bed rails from their place of storage to the place where the bed is located, we have constructed the side rails *d—d* each of two 90 sections of different sized angle iron and designated respectively by 11—11 and 12—12. The sections 11—11 which are the smaller, slide into the larger sections 12—12 and the sections are adjustably secured by 95 spring latches 13—13 which have noses 14—14 which pass through openings in the sections 12 and through openings in the sections 11 when the last-named openings align with the openings in the sections 12. The 100 angular shaped clips 15—15 are adapted to embrace the sections 12—12 and have bent

2
portions 16-16 which bear on the opposite faces of the sections 11-11 and thus clamp the sections together and prevent noticeable springing thereof under weight.

- 5 The lugs *e-e* are provided with suitable sockets 17-17 which are adapted to receive bosses 18-18 at the outer ends of the sections 11-11 and 12-12 and the said lugs are also provided with semi-circular recesses 10 19-19 which receive and form bearings for the cylindrical end portions 20-20 of the spring rolls 21-21. The spring 22 which is of a single length of woven wire of suitable pattern, has its opposite ends suitably 15 connected to the rolls 21-21 and since these are rotatably mounted in the lugs, a sufficient portion of the spring may be coiled upon either roll so as to leave an uncoiled portion between the rolls of a width corresponding to the adjusted width of the bed, it being understood that the spring will be 20 sufficiently long to present an uncoiled portion corresponding to the width of a double bed without detaching either of its ends 25 from the rolls 21. Each roll has at its opposite end portions, flanges 23-23 which by bearing on the lugs *e-e*, prevent longitudinal or endwise movement of the rolls and each roll also has a ratchet 24, any of whose 30 teeth may be engaged by a dog 25 which prevents turning of the spring roll. Each roll also has a non-cylindrical boss 26 to

receive the socket of a suitable crank handle which is employed for turning the rolls when it is desired to adjust the spring and 35 for tightening the spring by turning either roll, after the spring is adjusted to conform to the adjustment of the bed.

What we claim as new is:

1. An adjustable bed comprising a head 40 piece and a foot piece made up of telescoping sections, side rails connecting said head and foot pieces, extensible end rails carried by said head and foot pieces, spring pressed means for retaining said end rails 45 in adjusted position, and an adjustable spring including rollers having their opposite ends journaled in the said head and foot pieces.

2. An adjustable bed comprising a head 50 piece and a foot piece made up of telescoping sections, side rails connecting the said head and foot pieces, extensible end rails carried by the said head and foot pieces, and an adjustable spring including rollers having their opposite ends journaled in the said head and foot pieces. 55

In testimony whereof we affix our signatures in presence of two witnesses.

GEORGE BALLARD.
CLARE BALLARD.
